UNITED STATES PATENT OFFICE.

FRANK H. RYBACEK, OF RIVERSIDE, IOWA.

CORN-PLANTER.

SPECIFICATION forming part of Letters Patent No. 349,455, dated September 21, 1886.

Application filed February 2, 1886. Serial No. 190,614. (No model.)

To all whom it may concern:

Be it known that I, FRANK H. RYBACEK, of Riverside, in the county of Washington and State of Iowa, have invented a new and useful Improvement in Corn-Planters, of which the following is a specification, reference being had to the annexed drawings, forming a part thereof, in which—

Figure 1 is a plan view. Fig. 2 is a side elevation. Figs. 3 and 4 are detail views of parts of the drop-actuating mechanism.

Similar letters of reference indicate corresponding parts in the different figures of the drawings.

The object of my invention is to improve the corn-planter for which Letters Patent No. 236,525 were granted to me September 15, 1885.

My former invention consisted in a corn-planter having seed-droppers operated by sliding clips which were actuated by levers carrying daggers, which entered the ground and moved the clips, and through them operated the seed-droppers.

My present invention relates to an improved device for operating the daggers.

The frame A of the corn-planter is mounted upon an axle, B, and carries at its forward end two seed-boxes, C. A bar, D, which extends through guides a on the forward end of the frame A enters the lower part of each box, and carries on each end a seed-dropping valve of the usual construction. The bar D is provided near its ends and between the seed-boxes with transverse slots b, which receive the angled ends of the angled levers E, pivoted to the under side of the bars e of the frame A.

To opposite sides of the frame A are secured the guides F, upon which are placed movably the slides G. To each slide G is pivoted an arm, H, on the stud d, projecting at right angles on the outer face of the slide. A stop-arm, e, is attached to the stud d outside of the arm H, for engaging one end of a segmental rim, f, carried by the arm H, and arranged concentric with the stud d. The opposite end of the segmental rim f is engaged by a catch, g, pivoted to the face of the slide G and prolonged beyond its pivot, forming the arm h.

On the stud d, between the arm H and the slide G, is placed a bar, I, and to the extremity of the arm H is pivoted a bar, J. To the free ends of the bars I J is pivoted a dagger, K, the distance between the ends of the bars I J pivoted to the dagger being made greater than the distance between the opposite ends, to cause the points of the dagger to swing away from the stud d as it enters the ground, while the arm H is stationary. The pivot connecting the arm I with the dagger is prolonged over the side bar of the frame A, and is provided with a roller, L, and upon a post, M, supported by the frame A is pivoted a switch-arm, N, which is upwardly convex and rests upon the side bar of the frame A at a point within the extreme limit of the back-stroke of the dagger K. The switch-arm N is prolonged a short distance beyond its pivot to form the short inclined arm i.

At the rear end of the frame A, and in the path of the arm h of the catch g, is placed an arm, j, for engaging the arm h and tripping the catch g as the slide G completes its extreme rearward stroke. When the dagger K is moved backward in the machine, by engagement with the earth, the roller L passes under the switch-arm N, raising the arm, and allowing it to fall in front of the roller L, so that when the dagger K is moved forward, in a manner presently to be described, the roller L will ride over the switch-arm N, and the dagger will be raised out of the ground by the switch-arm N and carried forward, and will be dropped from the short arm i, when it will again enter the ground.

To the rear cross-bar, O, of the frame A is pivoted a two-armed lever, P, the opposite ends of which are connected with studs k, projecting upward from the slides G on opposite sides of the machine, so that when one of the slides and parts carried thereby moves in one direction the slide upon the opposite side of the machine will move in the opposite direction. Each slide G is provided with an angled plate, l, which extends under the side bar of the frame A, in position to engage the angled lever E as the slide G completes its forward excursion.

When the dagger K upon one side of the corn-planter is in engagement with the earth, 100

as shown in Fig. 2, the hook *g* engages the upper end of the segmental rim *f* on the arm *H*, the end of the segmental rim abutting against the stop *e*, thus holding the arm *H* in a fixed position, the arm being prevented from moving in one direction by the catch *g*, and being held from moving in the other direction by the stop *e*. The dagger *K* is held in its place in the ground by its own gravity, and also by a slight rearward inclination, which causes it to hold firmly in the ground. As the frame of the corn-planter is drawn forward the dagger *K* maintains a fixed position and holds the slide *G*, so that the guide *F*, carried by the frame, is moved through the slide *G*. The forward motion of the frame *A* carries the switch-arm *N* over the roller *L*, and finally brings the arm *H* of the catch *g* against the arm *j*, releasing the arm *H*, so that the dagger *K* may incline forward, as shown in Fig. 3, as it is carried along by the machine. At this moment the dagger *K* on the opposite side of the machine drops from the arm *i* of the switch-arm *N*, and, entering the earth, allows the catch *g* to engage the upper end of the segmental rim *f* and hold the arm *H* in a fixed position, as shown in Fig. 2. When the frame of the planter is moved forward in the manner already described, the dagger *K*, which was released on reaching the limit of its rearward excursion, is now quickly moved forward by virtue of its connection with the slide *G* and dagger *K* on the opposite side of the machine, and in its forward excursion it is carried up over the switch-arm *N*, and dropped down over the forward end of the switch-arm at the moment the dagger on the opposite side of the machine reaches the limit of its rearward excursion. In this manner the dagger upon one side of the machine alternates in its operation with the dagger upon the opposite side, and the progression of the daggers over the field is by a step-by-step movement, which resembles the act of walking.

Having thus described my invention, what I claim as new, and desire to secure by Letters Patent, is—

1. In a corn-planter, the combination of a guide, *F*, placed on the side of the planter-frame, the slide *G*, arranged to move thereon, the arm *H*, pivoted to the side of the slide *G*, the bar *I*, pivoted to the slide *G*, the bar *J*,

pivoted to the arm *H*, the dagger *K*, pivoted to the arms *I J*, and means for locking and releasing the arm *H*, substantially as herein shown and described. 55

2. In a corn-planter, the combination of the guides *F*, the slides *G*, the bar *I* and arm *H*, pivoted on the slide *G*, the bar *J*, pivoted to the arm *H*, the dagger *K*, pivoted to the arms *I J*, the catch *g*, pivoted to the slide *G* and arranged to engage the segmental rim of the arm *H*, the stop *e*, and means for connecting the slides *G* on opposite sides of the machine, substantially as herein shown and described. 65

3. In a corn-planter, the combination of the guide *F*, the slide *G*, the arm *H*, the bar *I*, pivoted to the slide, the bar *J*, pivoted to the arm *H*, the dagger *K*, pivoted to the bars *I J*, the roller *L*, carried by the dagger, and the pivoted switch-arm *N*, substantially as herein shown and described. 70

4. In a corn-planter, the combination of the guides *F*, the slides *G*, the arms *H*, provided with segmental rims *f*, the stops *e*, the catches *g*, having the arms *h*, the arms *j*, arranged to engage the arms *h* of the catches, the bar *I*, pivoted to the slide *G*, and the bar *J*, pivoted to the arm *H*, the dagger *K* and roller *L*, carried thereby, the pivoted switch-arm *N*, 80 the lever *P*, and rods connecting the same with the slides *G*, substantially as herein shown and described. 75

5. In a corn-planter, the combination of the guides *F*, slides *G*, arms *H*, provided with segmental rims *f*, the stop *e*, the catch *g*, the arms *I J*, and the dagger *K*, pivoted to the arms *I J*, the distance between the pivotal connections of the arms *I J* with the dagger *K* being greater than the distance between the pivotal connections of the opposite ends of the arms, 90 substantially as and for the purpose specified.

6. In a corn-planter, the combination of the seed-boxes *C*, bar *B*, levers *E*, slides *G*, provided with the arms *l*, dagger *K* and arms *I J*, 95 pivotally connected with the slides *G*, the lever *P* and rods connecting the lever with the slides *G*, and means for holding and releasing the dagger *K*, substantially as herein shown and described.
